(57) **CLAIM**

The ornamental design for a wheelbarrow as shown and described.

DESCRIPTION

FIG. 1 is a perspective view of the wheelbarrow in an assembled form showing our new design;

FIG. 2 is a perspective view of the wheelbarrow in the assembled form;

FIG. 3 is a first side view of the wheelbarrow in the assembled form;

FIG. 4 a second side of the wheelbarrow in the assembled form;

FIG. 5 is a front view of the wheelbarrow in the assembled form;

FIG. 6 is a rear view of the wheelbarrow in the assembled form;

FIG. 7 is a top view of the wheelbarrow in the assembled form;

FIG. 8 is a bottom view of the wheelbarrow in the assembled form;

FIG. 9 is a perspective view of the wheelbarrow in a stored form;

FIG. 10 is a perspective view of the wheelbarrow in the stored form;

FIG. 11 is a first side view of the wheelbarrow in the stored form;

FIG. 12 a second side of the wheelbarrow in the stored form;

FIG. 13 is a front view of the wheelbarrow in the stored form;

FIG. 14 is a rear view of the wheelbarrow in the stored form;

FIG. 15 is a top view of the wheelbarrow in the stored form; and,

FIG. 16 is a bottom view of the wheelbarrow in the stored form.

The broken line showing of the wheelbarrow forms no part thereof.

1 Claim, 14 Drawing Sheets
